WET-GRINDING APPARATUS

Bethune G. Klugh, Birmingham, Ala., assignor to Monsanto Chemical Company, St. Louis, Mo., a corporation of Delaware

Application May 26, 1950, Serial No. 164,321

2 Claims. (Cl. 241—98)

This invention relates to an improved wet-grinding system applicable to phosphatic and metalliferous minerals generally.

According to the present state of the art, continuous wet-grinding is usually carried out by passing materials in aqueous suspension into the feed end of a rod or ball mill, grinding the suspension and then treating the finely ground products by hydraulic classification so that the portion having the desired degree of subdivision is separated and recovered while the larger sizes are returned to the feed end of the mill for further grinding together with additional raw material. The desired fine-sized portion so obtained is then passed to dewatering equipment for the purpose of removing water not required for subsequent processing. This method is applicable to materials of substantially uniform density or to processes in which segregation of portions differing in density is not objectional. It is also limited to materials which are economically treated by conventional dewatering methods.

When the natural minerals or ores including naturally occurring phosphatic materials mixed with carbonaceous materials such as bituminous coal are subjected to wet-grinding and dewatering, it has been found that difficulties are encountered which are occasioned by the fact that bituminous coal is of a greatly differing density from that of minerals generally and also by reason of the fact that such phosphatic ores cannot be dewatered economically by reason of the presence therein of phosphatic colloidal particles and minerals. A further difficulty encountered in grinding coal by wet-grinding methods results from the fact that the fine particles of coal tend to float the larger particles and thus prevent a substantial part of the coal from passing into the grinding action of the rods or balls in the mill.

I have now found that mixtures of naturally occurring minerals or ores, including phosphatic materials with bituminous coal or other carbonaceous materials, may be ground by first forming a slurry of said materials containing a restricted amount of water and then introducing said slurry into a rod mill. The material is retained in the rod mill until the required degree of fineness has been obtained.

While the present invention is particularly applicable to the treatment of phosphatic ores and bituminous coal, it is also applicable generally to the treatment of other naturally occurring ores or minerals. Mixtures of naturally occurring ores or minerals and carbonaceous reducing agents suitable for a wide variety of metallurgical operations may be processed by means of the present invention. Examples of specific minerals which may be treated by my invention are the minerals containing iron, silica, aluminum, calcium, titanium, tungsten, chromium, vanadium, boron, manganese, zirconium and the like. Examples of carbonaceous reducing agents which may be employed in place of bituminous coal or in admixture therewith may be mentioned anthracite coal, coke, including petroleum coke, gilsonite pitch, carbon black, peat,

2

wood charcoal, wood sawdust or other forms of wood waste.

In order to illustrate my invention the treatment of Tennessee brown rock phosphate mixed with bituminous coal will be described in detail. In the case of these materials it is desired that the phosphate material and coal be ground to such a degree of fineness as to pass a 60 mesh screen. In order to grind the phosphate rock and coal to this degree of fineness I first form an aqueous slurry mixture containing at least 30 percent by weight of water, but not in excess of 40 percent by weight of water by the means hereinafter described and introduce said slurry into the rod mill where it is subjected to the grinding action of the rods until the required degree of fineness is obtained.

The preliminary slurry mixture which is introduced into the mill as above-mentioned is formed by repeatedly raising and dropping the solid constituents of the slurry by mechanical means into the aqueous phase of the slurry until substantial uniformity has been obtained. Such repeated raising and dropping tends to break up the larger lumps and aggregates of the solid ingredients of the slurry batch, thereby tending to hasten the formation of a uniform, flowable aqueous slurry. This agitation of the solids with the water disintegrates the plastic clay-like aggregates and wets the carbonaceous constituents therewith, forming a more permanent unsegregable slurry mix. The said slurry batch is then permitted to flow by gravity, assisted by said mechanical means, into the empty rod mill. The entrance port and the exit port of the rod mill are then closed and grinding is permitted to take place for the necessary period of time. When the desired degree of fineness has been achieved, the discharge means of the mill is brought into operation and the contents thereof are discharged for further processing.

Apparatus suitable for performing the above operations and comprising a part of the present invention, is illustrated in the accompanying drawings, whereof:

Fig. 1 illustrates in cross section the slurry preparation and grinding means, Fig. 2 illustrates in sectional view a discharge device for unloading the ground slurry of the mill at the completion of the operation, said section being taken at section A—A as indicated in Fig. 1.

In the drawing, in Fig. 1, rod mill 1 is rotated upon a tire 2 running on rolls 3 in the usual manner, the rolls 3 being mounted upon support 4. The feed end of the mill is supported by bearing 5. Partition wall 6 is located adjacent the discharge end of the mill at such a distance from the end wall of the mill 8 so as to provide space for the rotating scoop discharging blades 7. Blades 7 are also shown in Fig. 2 and serve to lift the pulp flowing through annular opening 9 into the compartment containing the said blades to the central discharge outlet 10. Discharge outlet 10, located in the end wall 8 of the mill, is provided with a lip 11. 12 is a stationary discharge chute or housing surrounding lip 11 for collecting and conveying the discharged pulp. Discharge opening 10 is provided with a closure valve disk 13 coacting with discharge opening 10. Said valve disk 13 is carried by shaft 14 connected by rotatable coupling 16 with shaft 17. Shaft 17 extends into hydraulic cylinder 18 and is joined to a conventional piston moving within said cylinder. By actuating the hydraulic cylinder 18, it is, accordingly, possible to move valve seat 13 into closed or open position at will.

At the feed end of the mill, the bearing 5 is supported by foundation 19. Passing through bearing 5 is tubular shaft 20 fixedly joined to end wall 21. The outboard end 22 of shaft 20 is connected to a horizontal, stationary pipe 23, the joint therewith being made tight by means of packing gland 24. Extending vertically upward from pipe 23 and attached thereto is pipe 25, which is joined

to conical bottom 26 of tank 27, the latter being supported by I-beams 28, which in turn are supported by suitable means not shown. Within tank 27 is a cylindrical conveyor housing 29, the lower end 30 thereof being supported by struts 31 at some distance above the apex of conical tank bottom 26. An open port or passage for the tank contents is thus provided between the end 30 of housing 29 and tank bottom 26. The upper end 32 of housing 29 is provided with conical baffle 33.

Arranged within housing 29 is a vertically disposed screw conveyor 34, the shaft 35 of which is supported at its lower end by bearing means 36. The upper end of shaft 35 is connected to reduction gear 37, which in turn is driven by reversible motor 38. Adjacent the upper end of shaft 35 and fixedly attached thereto so as to rotate therewith is conical baffle 39. Baffle 39 is arranged somewhat below the upper end 40 of tank 27. The upper end 32 of screw conveyor housing 29 is likewise below the upper end 40 of tank 27 and also below baffle 39.

A stock supply chute 41 is arranged at end 40 of tank 27 so that stock supplied to chute 41 falls upon conical, revolving, distributing baffle 39. Stock is carried to chute 41 by belt conveyor means 42.

Rod mill 1 is provided with conventional rods 43 and is driven in conventional manner by means of motor 44, pinion 45 and ring gear 46.

In order to control discharge of stock from tank 27 through pipe 25 into mill 1, I provide valve means 47 actuated by hydraulic cylinder 48. Valve means 47 is shown in the drawing in open position. However, by operation of hydraulic cylinder 48 said valve means may be moved upwardly so as to contact seat 49, whereby closure of pipe 25 is effected.

For the purpose of cleaning out the interior of section 23, including valve means 47, should this at any time be necessary, I provide water supply connection 50 controlled by valve 51. Water supply pipe 52 is arranged at chute 41 so as to permit the addition of a proportioned amount of water to tank 27 for the purpose 40 of preparing the aqueous slurry therein.

The operation of my invention as applied to the preparation of a phosphatic or bituminous coal slurry will now be described.

Hydraulic cylinder 48 is first actuated forcing valve 47 into contact with seat 49, phosphatic ore and coal 45 both preferably of less than one-half inch size is supplied by belt conveyor 42 and discharged into chute 41. Water in an amount sufficient so as to supply from 30% to 40% by weight of the total contents of the charge in tank 27 is also admitted thereto. At the same time, motor 38 is placed into operation, the direction of rotation thereof being such as to cause screw conveyor 34 to lift tank contents upwardly through housing 29 to the top 32 thereof. The stock so raised then falls over conical baffle 33 and drops down into the bottom section 26 and tank 27. The operation of conveyor 34 is continuous in this manner while tank 27 is being loaded with its portioned charge of water, phosphatic material and coal, by this means effecting disintegration and breaking down of coal and ore lumps. At the same time the water is intimately mixed with the mineral and coal particles causing a coarse slurry to be formed. While the correct weights of water, ore and coal are being supplied to tank 27 in the manner described, the operation of conveyor 34 is continued and as a matter of fact said operation of conveyor 34 is maintained until the previously ground charge in rod mill 1 has been removed therefrom and the mill is emptied.

When the grinding of the previous charge is completed to the desired degree in the rod mill and it is emptied through opening 10 and it is desired to fill rod mill with a new charge, hydraulic cylinder 18 is actuated so as to bring valve 13 into contact with seat 10, whereby closure is effected, hydraulic cylinder 48 is also actuated 75

so as to move valve 47 downwardly into its lower and open position. At the same time the direction of rotation of screw conveyor 34 is reversed so that the stock contained in tank 27 is forced downwardly through pipe 25 into pipe 23, thence into pipe 20 and into mill 1. When the contents of tank 27 have been emptied into the mill 1, valve 48 is again closed by upward movement and positioning of valve 48 against valve seat 49. Prior thereto it may be desirable, when treating certain types of ores, to introduce a small amount of water into pipe 23 by opening valve 51 in pipe 50. This will serve to wash off any lumpy materials which might cause valve 48 to fail to make a tight seat on valve seat 49. The wash water and any solids carried thereby will then flow into mill 1.

During the operation above described, the mill 1 has been maintained in continuous rotation. Upon receiving its load of water, ore and coal the grinding action of rods therein will be carried out in conventional manner. When the particles of ore and coal have been ground so as to pass a 60 mesh screen, or other specific desired particle size, the mill is emptied of its contents by opening valve 13 by operation of hydraulic cylinder 48. The ore slurry within the mill flows through annular space 9, is lifted by flights or vanes 7 and thus caused to flow out into discharge chute 12, thus emptying the mill. When the mill has thus been emptied, it is ready to receive another charge of stock which during this time, has been prepared in tank 27 as already described.

The herein-described combination of rod mill arranged with feed and discharge means, said feed means including a vertical, reversible screw conveyor and a supply tank surrounding said conveyor and means connecting said tank with said feed means may be totally automatically controlled by time cycle control means. By suitable time cycle control actuating motor 38, hydraulic mill feed valve cylinder 48 and hydraulic mill discharge cylinder 18, it is possible to maintain continuous operation of mill 1 and obtain an output of ore slurry without employing the conventional closed circuit grinding and classification means. The ore slurry containing at least 30%, but not in excess of 40%, of water produced by the herein-described invention may be further treated by the agglomerating technic and apparatus described and claimed in pending application Serial No. 164,322, filed May 26, 1950, now Patent No. 2,695,221, the inventors of which are myself and Riley N. Weston, said application being assigned to the same assignee as is the present case.

What I claim is:

1. A horizontally rotatable rod mill including axially arranged feed and discharge means, said feed means including a vertically disposed reversible screw conveyor arranged in a stationary cylindrical housing, a tank surrounding said housing and extending above the upper end thereof, a tubular conduit connecting said feed means with said tank and feed closure means arranged within said tubular conduit.
2. In combination, a horizontally rotatable rod mill provided with axially arranged feed and discharge means, closure means for said feed and discharge means, said feed means including a vertically disposed reversible screw conveyor arranged in a stationary cylindrical housing, a tank surrounding said housing and extending above the upper end thereof, a tubular conduit connecting said feed means with said tank, said feed closure means being contained within said tubular conduit.
